(57) **CLAIM**

The ornamental design for an add on pocket for folder, as shown and described.

DESCRIPTION

FIG. 1 is a front perspective view of the add on pocket for folder, showing our new design.

FIG. 2 is a front elevational view thereof.

FIG. 3 is a rear elevational view thereof.

FIG. 4 is a side elevational view thereof, the opposite side being a mirror image thereof.

FIG. 5 is a top plan view thereof; and,

FIG. 6 is a bottom plan view thereof.

The broken lines are directed to environment; the broken lines form no part of the claimed design.

1 Claim, 6 Drawing Sheets(56)
